UNITED STATES PATENT OFFICE.

LOUIS J. MUELLER, JR., OF MILWAUKEE, WISCONSIN, ASSIGNOR TO L. J. MUELLER FURNACE CO., OF MILWAUKEE, WISCONSIN, A CORPORATION OF WISCONSIN.

SMOKE-PIPE CONNECTION AND CHECK-DAMPER FOR HEATERS.

1,048,197.

Specification of Letters Patent.

Patented Dec. 24, 1912.

Application filed December 24, 1910. Serial No. 599,180.

To all whom it may concern:

Be it known that I, Louis J. Mueller, Jr., a citizen of the United States, residing at Milwaukee, in the county of Milwaukee and State of Wisconsin, have invented certain new and useful Improvements in Smoke-Pipe Connections and Check-Dampers for Heaters, of which the following is a specification, reference being had to the accompanying drawing, forming a part thereof.

The main object of this invention is to provide for the connection of the smoke pipe with a heater either in a vertical or a horizontal position, and to adapt a check damper for use with such smoke flue in either position.

It consists in the construction, arrangement and combination of parts as hereinabove particularly described and pointed out in the claims.

In the accompanying drawing like characters designate the same parts in the several figures.

Figure 1 is a side elevation of the smoke hood and check damper of a boiler, furnace or other heater embodying the invention, a portion of the dome and jacket of the heater being shown, and the hood being arranged for connecting the smoke pipe with the top thereof; Fig. 2 is an end elevation of the smoke hood and damper as seen from the right with relation to Fig. 1; Fig. 3 is a view similar to Fig. 2, showing the check damper reversed and connected with the top opening of the hood, so that the smoke pipe may be connected in a horizontal position with the end opening of the hood; Fig. 4 is a detail view of the damper frame by itself; Fig. 5 is a similar view of the damper detached; and Fig. 6 is an enlarged section on the line 6—6, Fig. 2, showing one of the damper hinges.

Referring to Figs. 1 and 2, *a* designates the smoke hood of a heater which is preferably cast or made in the form of a cylindrical pipe, and is bolted or otherwise fastened in a horizontal position to the dome *b* or upper part of the heater. It is formed at its outer end and on top in vertical and horizontal planes with openings and collars *c* and *d* for the interchangeable connection therewith of the smoke pipe *e*, which is indicated by dotted lines in Fig. 1 as con-

nected with the top opening and collar *d* in 55 a vertical position. A flanged check damper frame *f*, interchangeably fitted in the end and top openings of the hood is detachably fastened thereto by bolts *g* engaging lugs *h* cast inside of the hood. This 60 frame is formed on the outer side with an oblique or inclined damper seat *i*, and on the high and low sides thereof with pivot bearings *j*. *k* is a check damper formed or provided on one side with hinge or pivot pins 65 *l*, which are interchangeably fitted to the bearings *j* on either side of the damper frame, and are confined therein by caps *m* removably fastened to the frame, as shown in Fig. 6, by bolts *n*. These caps fit over 70 the sides and outer ends of the bearings *j*, which project from the frame and are held independently of the bolts *n* against endwise displacement in one direction by lugs *o* cast on the frame. The hinge or pivot pins *l* 75 are formed or provided with lugs *p* which by engagement with lugs or projections *q* on the bearings *j*, limit the opening of the damper in either of its positions at the end or the top of the smoke hood *a*. The frame *i* is formed on opposite sides with latch lugs *r*, which co-operate with a latch *s* pivoted to one side of the damper and having a series of teeth for holding the damper open more or less, the latch being weighted so 85 that when it is released it will move out of engagement with whichever lug *r* it is arranged to operate.

In order to connect the smoke pipe *e* with the end opening and collar *c* of the smoke 90 hood, which is often necessary or desirable the check damper is reversed and connected with the top opening and collar *d*, as shown in Fig. 3. This is accomplished by simply removing the bolts *n* and shifting them with 95 the caps *m* and hinge or pivot pins *l* of the damper, to the bearings *j* on the opposite or high side of the inclined seat *i*, and by disengaging the bolts *g* from the lugs *h*, transferring the damper and damper frame 100 to the top opening and securing it in the position shown in Fig. 3 in like manner to corresponding lugs inside of the collar *d*, so that the damper when closed will incline 105 downwardly from its hinged side in both positions, as shown by Figs. 1 and 3.

The changes above mentioned are easily and quickly made, and the heater is thus

adapted to varying conditions requiring the smoke pipe to be taken therefrom either vertically or horizontally.

I claim:

- 5 1. The combination with a smoke hood having an opening in one end and an opening in the upper side thereof for interchangeable connection therewith of a smoke pipe and a check damper, of a damper frame 33 interchangeably fitted to said openings and having an inclined damper seat and means at the higher and lower sides of said seat for hinging the damper to the frame, and a damper adapted to be detachably hinged 15 to said frame at either the higher or lower side of said seat and to be closed by gravity against its seat in either position of the damper frame.
2. The combination with a smoke hood 20 having end and side openings one in a vertical and the other in a horizontal plane for interchangeable connection therewith of a horizontal or vertical smoke pipe and a check damper, of a damper frame interchangeably fitted to said openings and having on opposite sides thereof pivot bearings for the damper, a reversible damper having pivot pins interchangeably fitting said bearings and detachable caps for securing said 25 pivot pins in the bearings on either side of the frame.
- 30

3. The combination with a smoke hood having end and side openings for the interchangeable connection therewith of a smoke pipe and a check damper, of a damper frame 33 interchangeably fitted to said openings and having on opposite sides thereof pivot bearings for the damper, a reversible damper having pivot pins interchangeably fitting said bearings and provided with stop lugs 40 for limiting the opening of the damper, and means for confining said pivot pins in the bearings on either side of the frame.

4. The combination with a smoke hood having end and side openings for the interchangeable connection therewith of a smoke pipe and a check damper, of a damper frame 45 interchangeably fitted to said openings and provided on opposite sides with pivot bearings and on the remaining sides 50 with latch lugs, and a reversible damper having pivot pins interchangeably fitting said bearings and a pivoted latch adapted to work with either lug on the damper frame according to the position of the 55 damper.

In witness whereof I hereto affix my signature in presence of two witnesses.

LOUIS J. MUELLER, JR.
